US00D649588S

(12) **United States Design Patent**
Clegg et al.

(10) **Patent No.:** US D649,588 S
(45) **Date of Patent:** ** Nov. 29, 2011

(54) **VIDEO BOOK**

(75) Inventors: **Timothy P. Clegg**, Manhattan Beach, CA (US); **Michael D. Ronk**, Lawndale, CA (US)
(73) Assignee: **Americhip, Inc.**, Los Angeles, CA (US)
(**) Term: **14 Years**
(21) Appl. No.: **29/397,890**
(22) Filed: **Jul. 22, 2011**

Related U.S. Application Data

(60) Division of application No. 29/368,489, filed on Aug. 24, 2010, now Pat. No. Des. 642,611, which is a continuation-in-part of application No. 29/363,757, filed on Jun. 14, 2010, now Pat. No. Des. 629,458, which is a continuation-in-part of application No. 12/413,343, filed on Mar. 27, 2009, now Pat. No. 8,011,122, which is a continuation-in-part of application No. 12/263,277, filed on Oct. 31, 2008, which is a continuation-in-part of application No. 12/199,740, filed on Aug. 27, 2008, now abandoned.

(57) **CLAIM**

The ornamental design for a video book, as shown and described.

DESCRIPTION

FIG. 1 is a perspective view of an embodiment of the present invention;
FIG. 2 is a top plan view of the present invention shown in FIG. 1;
FIG. 3 is a left side elevational view of the present invention shown in FIG. 1;
FIG. 4 is a right side elevational view of the present invention shown in FIG. 1;
FIG. 5 is a bottom plan view of the present invention shown in FIG. 1;
FIG. 6 is a top elevational view of the present invention shown in FIG. 1;
FIG. 7 is a bottom elevational view of the present invention shown in FIG. 1;
FIG. 8 is a perspective view of a second embodiment of the present invention;
FIG. 9 is a top plan view of the present invention shown in FIG. 8;
FIG. 10 is a left side elevational view of the present invention shown in FIG. 8;
FIG. 11 is a right side elevational view of the present invention shown in FIG. 8;
FIG. 12 is a bottom plan view of the present invention shown in FIG. 8;
FIG. 13 is a top elevational view of the present invention shown in FIG. 8;
FIG. 14 is a bottom elevational view of the present invention shown in FIG. 8;
FIG. 15 is a perspective view of a third embodiment of the present invention;
FIG. 16 is a top plan view of the present invention shown in FIG. 15;
FIG. 17 is a left side elevational view of the present invention shown in FIG. 15;
FIG. 18 is a right side elevational view of the present invention shown in FIG. 15;
FIG. 19 is a bottom plan view of the present invention shown in FIG. 15;
FIG. 20 is a top elevational view of the present invention shown in FIG. 15; and,
FIG. 21 is a bottom elevational view of the present invention shown in FIG. 15.
The broken line showing of portions of the video book is included for the purpose of illustrating environmental structure and forms no part of the claimed design.
